UNITED STATES PATENT OFFICE.

ALFRED P. BOHLINGER, OF ST. LOUIS, MISSOURI.

CURTAIN-STRETCHER.

SPECIFICATION forming part of Letters Patent No. 328,278, dated October 13, 1885.

Application filed May 16, 1885. Serial No. 165,751. (No model.)

To all whom it may concern:

Be it known that I, ALFRED P. BOHLINGER, of the city of St. Louis, in the State of Missouri, have invented certain new and useful Improvements in Curtain-Stretchers, &c., of which the following is a full, clear, and exact description, reference being had to the accompanying drawings, forming part of this specification, in which—

10 Figure 1 is a top view of my improved frame and stretcher. Fig. 2 is an end view of the same. Fig. 3 is an enlarged detail top view with the curtain removed. Fig. 4 is an enlarged detail top view of one of the sides of the frame, illustrating the joint, which is shown disconnected. Fig. 5 is an edge view of same. Fig. 6 is a similar view to Fig. 4, showing the joint connected. Fig. 7 is a similar view to Fig. 5, showing the joint secured. Fig. 8 15 is a transverse section taken on line 8 8, Fig. 6. Fig. 9 is a perspective top view illustrating the manner of securing the tenter-hooks to the flaps or canvas. Fig. 10 is a similar view reversed, showing a section of the under side of the flap and the manner of looping the cord that attaches the tenter-hooks.

Similar letters of reference illustrate corresponding parts in all the figures.

The invention relates to an improved curtain-stretcher, quilting-frame, &c., that is capable of being adjusted to the size and shape of the article or goods to be operated on, and has a provision not only to fasten the main body of the curtain, &c., by tenter-hooks, but also 20 has a device by which the finest lace scallops and fringes that border the curtain can be laid out so that in drying it will maintain its required position without applying the main force of the stretcher to the more delicate parts 25 of the curtain.

The invention consists of a frame of four or more bars or strips. I have shown a frame with six sections; but I do not confine myself to that number, for it is evident that the number may 30 be increased or diminished without departing from the essential features of my invention. The sides of this frame, as shown, are each composed of two pieces, which are securely connected at their junction by tenon and mortise joints. The joint is still further stiffened

35 by a metallic split sleeve that slides over it and in conjunction with pins or screws that pass through both sleeve and joint clamps and tightens the same, making a completely stiff joint. The ends of the frame as shown are 55 each composed of a single piece; but I do not so confine myself, for it is evident that they may be made in double or multiple sections jointed together, as shown and described, in the sides. Flaps composed of canvas or other 60 fabrics are attached to the strips and form a convenient provision for the attachment of the tenter-hooks. These flaps form an important and novel feature in the device, making a soft and level bed (after or at the time the main 65 body of the curtain is stretched) on which to lay out and join the fine-lace scallops and fringed borders of the curtain. The frame is held at its corner joints by metallic screw-clamps, as usual.

70 Referring to the drawings, A A are the side and end pieces of the frame, and A' and A" are respectively the tenon and scarf or jaws of the mortise that compose the middle joints of said frame.

75 B B are the clamps that secure the corners of the frame, and B' B' the thumb-screws by which they are fastened.

C C are the metallic sleeves that slide over and sustain the middle joints of the frame, and 80 C' C' the pins or screws that pass through the sleeve and corresponding members of the joint and secure the same.

D and D' are respectively the narrow and broad flaps of canvas or other fabric to which 85 the tenter-hooks and curtain are attached.

E E are the tenter-hooks for holding the curtain in the process of stretching, and E' the looped cords that secure the hooks to the 90 fabric. (See Figs. 9 and 10.)

F is the curtain in frame. (See Fig. 1.)

In operating the stretcher when the curtain or other goods are of sufficient size to require double sections on either sides or ends, the corresponding pieces are first securely fitted together, the metallic sleeve slid over the joint onto its seat, and the pin or screw C', passing through sleeve and joint, is tightened, forming a stiff joint. The curtain is secured by the tenter-hooks to the stretcher, the scalloped or 95 100

fringed lace border being laid out on and pinned to the wide flap at the same time or after the curtain is stretched. The side and end sections of the frame are now brought relatively 5 into their right positions and drawn back to stretch the curtain to the extent desired, and the corner-clamps tightened by their thumb-screws then rigidly hold the frame to its work.

The need of such a device has long been felt.

- 10 In stretching curtains heretofore great difficulty has been experienced in laying out and securing the fine and delicate lace scallops and fringes in the required position while in the course of stretching and drying, as it is evident those parts are of too delicate a structure to stand the strain required to stretch the main body of the curtain.
- 15 The device is also useful for many other purposes—such as in quilting, &c. Being a

“knockdown” frame, when taken apart it 20 can be put away in a very small compass.

I claim as my invention—

1. In a curtain-stretcher, &c., the combination of adjustable frame A A, tenon-mortise joint A' A'', split sleeve C, and fastening-screw 25 C' inserted through the sleeve-tenon and mortise-jaws, all substantially as shown and described, for the purpose set forth.

2. In a curtain-stretcher, &c., the combination of adjustable frame, attachment flaps D 30 and D', tenter-hooks E, and cord E', looped through the fabric and eyes of the hooks and returned on itself, all substantially as shown, and for the purpose set forth.

ALFRED P. BOHLINGER.
